United States Patent Office

Des. 188,043
Patented May 31, 1960

188,043

DOOR

Paul Tyson 142 Manchester, Detroit, Mich.

Filed July 26, 1956, Ser. No. 42,401

Term of patent 14 years

(Cl. D13—1)

Fig. 1 is a front elevational view of a door showing my new design with hinges and a handle being shown in broken lines for illustrative purposes only.

Fig. 2 is an enlarged cross sectional view taken on line 2—2 of Fig. 1 showing the contour of the door adjacent an edge.

Fig. 3 is an enlarged fragmentary view illustrating a corner portion of the door.

I claim:

The ornamental design for a door, substantially as shown and described.
